INVERTIBLE BOOSTER CHAIR FOR A CHILD

Raymond A. Lo Turco, Columbus, Ind., assignor to
Hamilton Cosco, Inc., Columbus, Ind.

Filed Sept. 21, 1972, Ser. No. 291,003

Term of patent 14 years

Int. Cl. D6—01

U.S. Cl. D6—3

Fig.1

Fig.2

Fig.3

Fig.4

Fig.5

Fig.6

Fig.7

FIG. 1 is a perspective view of a invertible booster chair for a child showing my new design;

FIG. 2 is a top elevation thereof;

FIG. 3 is a front elevation thereof;

FIG. 4 is a bottom elevation thereof;

FIG. 5 is a perspective view of the booster chair shown in FIG. 1, but showing said chair in an inverted orientation;

FIG. 6 is rear elevation of the chair in the orientation shown in FIG. 5; and

FIG. 7 is a side elevation of the chair in the orientation shown in FIG. 5.

I claim:

The ornamental design for an invertible booster chair for a child, as shown.
